N. Y., A CORPORATION OF NEW YORK

FLUSHING ARM FOR SANITARY WATER CLOSET ATTACHMENTS

Application filed February 19, 1931. Serial No. 516,858.

This invention relates to plumbing appliances and more particularly refers to improvements in sanitary attachments for water closets and bidets of the type where a nozzle bearing arm is brought from an inoperative to an operative position for directing a jet of fluid against the body of the occupant of the seat for cleansing purposes.

Sanitary water closet attachments of the type to which this invention refers have been described and claimed by us in our copending applications, entitled: Method of and apparatus for sanitary cleansing, Ser. No. 483,234; Cleansing nozzle for water closet, Ser. No. 485,440; Sanitary bowl with hydraulic dryer, Ser. No. 487,410; Sanitary water closet attachments, Ser. No. 496,898.

In the application last mentioned especially, we have described an arrangement in which a flushing or water delivery arm is brought by the cam action exerted by a plunger member from an inoperative position under the rim of the water closet bowl to an operative position where the nozzle provided at the end of said arm comes to occupy a position within the bowl in which its axis remains on a vertical longitudinal plane passing through the center of the bowl and is upwardly inclined towards the rear 30 of the bowl as advocated in our copending application, Ser. No. 483,234.

Water under pressure issuing from the nozzle will therefore be projected in an upwardly inclined direction towards the rear 35 of the bowl. More particularly the direction of the fluid jet issuing from the nozzle will be such that the fluid under pressure will strike directly against the body outlet of the occupant of the seat in connection with 40 which the cleansing operation is to be performed.

In the arrangement described in said application, the flushing or water delivery arm is caused to travel in a substantially horizontal direction between its two extreme positions, the underside of the rim of the bowl being just about at the level that the nozzle should occupy when brought to its operative position. Due to this manner of operation, 45 the arm remains constantly within the bowl 50

and is exposed not only to the action of the flushing water issuing from the rim of the bowl, but also to contamination by residues which might remain in the bowl after improper flushing or otherwise. Sanitary considerations have therefore lead us to believe that it is preferable for the flushing or water delivery arm to remain normally in a position where the water used to flush the bowl and residual matters cannot reach it or contaminate it.

Accordingly, the primary object of our invention is to provide in a sanitary attachment of the character specified, a flushing or water delivery arm so arranged that when inoperative it rests above the bowl and away from the cavity of the bowl, while when brought to operative position its nozzle will remain below the level of the bowl with its axis remaining on a vertical longitudinal plane 70 passing through the center of the bowl as previously described.

Another object is to provide in a device of the character specified, where a flushing or water delivery arm is movable from an inoperative position above the bowl to an operative position within the bowl, means for effecting the movement of said arm, whereby said arm is subjected to both a translatory and a rotatory movement, this making it possible for said arm to remain flat above the bowl when in its inoperative position and to lay in a vertical or nearly vertical plane when brought to its operative position within the bowl.

A further object is to provide in a device of the class specified where a flushing arm is caused to move from an inoperative position above the bowl to an operative position within the bowl, operating means of a novel and improved design, whereby said arm can be caused to acquire a translatory and a turning movement through a single movement of the operating member.

A still further object is to provide in a device of the character specified, where an operating member is caused by a single movement to impart to the flushing arm both a translatory and a rotatory movement, means whereby the same operating member is en-

abled by a continuation of its movement to also control the fluid flow through said flushing arm.

Other objects and advantages of the present invention will more fully appear as the description proceeds and will be set forth and claimed in the appended claims.

Our invention is illustrated by way of example in the accompanying drawings, in which:

Fig. 1 is a vertical cross section of a water closet bowl equipped with a device embodying our invention;

Fig. 2 is a vertical longitudinal section of said bowl;

Fig. 3 is a plan view in an enlarged scale of said attachment showing the flushing arm in its inoperative position;

Fig. 4 is a side view in elevation thereof;

Fig. 5 is an end view in elevation of the same partly sectioned in an enlarged scale through line 5—5 of Fig. 4;

Fig. 6 is a fragmentary side view in elevation in an enlarged scale of the outer end of said attachment;

Fig. 7 is a fragmentary longitudinal section of the attaching end of the flushing arm;

Fig. 8 is a view in perspective of the front support for the flushing arm;

Fig. 9 is a fragmentary plan sectional view in an enlarged scale of the valves controlling the fluid supply through line 9—9 of Fig. 6;

Fig. 10 is a vertical section thereof, through line 10—10 of Fig. 9;

Fig. 11 is a front elevation of the housing for the valve controlling plunger;

Fig. 12 is a plan view thereof;

Fig. 13 is a side elevation thereof;

Fig. 14 is a vertical section thereof, through line 14—14 of Fig. 13;

Fig. 15 is a front elevation of the valve controlling plunger;

Fig. 16 is a side elevation thereof;

Fig. 17 is a plan view thereof;

Fig. 18 is a view in perspective of one of the valves shown in Figs. 10, 11;

Fig. 19 is an end view thereof;

Fig. 20 is a fragmentary front elevation illustrating a different type of valve operating plunger; and

Fig. 21 is a similar view illustrating a still different type of valve operating plunger.

Referring to said drawings, 20 designates a toilet bowl of usual construction comprising a base 21 and a rim 22 formed with a passage 23, through which water flows through a suitable source of supply in order to flush the bowl in the customary manner.

The bowl is provided with a seat 24 on top, hinged at 25 to the rear of the bowl. The lower surface of the seat 26 is usually provided with rubber spacing feet 27 resting upon the top of rim 22 causing a clearance 28 to remain between the top of the bowl and the lower surface of the seat. The device il-

lustrated, comprises a supporting frame 29 upon which all the operating parts are mounted, said frame having a hook shaped arm 30 inwardly extending therefrom, said arm being adapted to embrace the rim portion of the bowl and cooperating with two clamping screws 31, 32, in adjustably securing the device in position.

To this end, arm 30 is composed of a horizontal section 33 inwardly extending from the top of upright 34 of frame 29 and a downwardly turned end section 35 embracing the inner portion of rim 22. Arm 30 is preferably secured in position by means of a screw or screws, such as 36 so as to make it easier to set the device in position and to remove it therefrom. Clamping screws 31, 32 are located one at each side of upright 34 and can be caused to firmly grip the rim portion of the bowl so as to securely fasten the frame in position.

It will be observed that by adjusting the relative positions of said screws, the downwardly directed section 35 of arm 30 can act as a fulcrum for the frame, which can thus be placed in the proper position with respect to the bowl. Said frame essentially comprises an inner cross member 37 and an outer cross member 38 joined by two substantially horizontal hollow members 39, 40.

The inner cross member 37 is provided with a passage leading from side opening 41 to the passage 42 of horizontal member 40. Said inner cross member is also provided with a side opening 43 leading to the passage 44 of horizontal member 39.

Said openings 41, 43 are threaded or otherwise machined to receive a hot and a cold water pipe respectively, such as shown at 45. The outer cross member 38 comprises a central hollow body 46 and two extensions 47, 48 laterally projecting therefrom in opposite directions.

Central body 46 is bored to form a vertical chamber 49, closed at the top except for a central opening through which may project the stem 50 upwardly extending from the valve controlling plunger 51. The open lower end of chamber 49 is threaded to receive a plug 52 which retains in position the housing 53 inserted within said chamber. The upper surface of said housing is preferably cupped as shown at 54 while the bottom surface 55 of chamber 49 is cupped in the opposite direction so that a packing 56 may be compressed between said two cupped or concave surfaces when pressure is exerted by plug 52 against the lower surface 57 of housing 53.

Housing 53 is formed with a central chamber 58, which is open at the lower end and closed at the top except for a central passage 59 for the stem 50 of a valve controlling plunger. Said valve controlling plunger comprises a body portion 60 which registers with and is vertically movable within cham-

ber 58, and stem 50 which as stated projects through the top of housing 53 and the top of central body 46.

The housing 53 is provided with two diametrically opposite vertical slots such as 61 through which are slidably inserted cam acting members 62, 63 laterally projecting from body 60 of the valve controlling plunger in diametrically opposite directions.

10 A spring 64 is interposed between the plug 52 and the bottom surface of the valve controlling plunger and tends to constantly maintain the valve controlling plunger in its upward position against the upper surface of 15 chamber 58, as Fig. 10 clearly shows.

Extensions 47, 48 are each provided with a horizontal passage 65, 66 through which are inserted stem portions 67, 68 of valves 69, 70. The slots 61 in housing 53 are accordingly 20 enlarged as at 71 to permit the tip ends of said stems 67, 68 to project through the walls of housing 53. The head portions of said valves are housed within chambers 72, 73 extending from the outer ends of extensions 25 47, 48 to the seats of said valve and to passages 65, 66. Chambers 72, 73 communicate with passages 44, 42 respectively of horizontal members 39, 40, and are closed by plugs 74, 75, springs 76, 77 being interposed between 30 said plugs and said valves and constantly holding the valves against their seats.

By virtue of this construction, it will be seen that if the valve controlling plunger is depressed against the action of spring 64, 35 the two cam acting members 62, 63 will gradually force out valves 69, 70 against the action of springs 76, 77 and cold and hot water will be admitted to chamber 49.

The middle portion of housing 53 is turned 40 down as at 78, so as to form an annular passage with the inner surface of chamber 49, and in correspondence of said annular passage is provided another passage 79 extending through a lug 80 rearwardly projecting 45 from central body portion 46. The water admitted to chamber 49 will therefore find its way through passage 79 to chamber 81 provided within lug 80. Said chamber 81 is open at the top and is threaded to receive the 50 threaded lower end 82 of a hollow stud 83 forming a vertical pivotal support for the flushing or water delivery arm assembly.

Said assembly comprises the delivery arm 84 proper which is carried by a chuck 85 rotatably mounted on the enlarged outer end 86 of a horizontal tubular member 87, the rear end of which is screwed into and carried by a supporting member 88 as shown at 89, said supporting member 88 being rotatably 60 mounted upon the enlarged upper end 90 of stud 83.

All the connections between these various parts are made so as to insure tightness while at the same time, permitting rotation of supporting member 88 about a vertical axis and

rotation of chuck 85 and flushing arm 84 carried thereby, around the horizontal axis of said chuck and of tubular member 87. To this end, a threaded hollow nut 91 is inserted over stud 83 and is screwed into the lower end 70 of supporting member 88 as shown at 92. A packing is provided between nut 91 and supporting member 88 by inserting the washer 93 against the shoulder formed by the neck portion of stud 83 and its enlarged portion 90 and then inserting a packing ring 94 between said washer and the inner surface of nut 91. In this manner, a pivotal connection is established between stud 83 and supporting member 88 which prevents said supporting member from coming off said stud and at the same time permits said supporting member to rotate upon said stud, packing ring 94 insuring the necessary tightness between these 80 various parts.

Stud 83 is provided with a central axial passage 95 which is closed at its upper end and which communicates by means of radial passages 96 with an annular passage 97 formed in the outer surface of the enlarged portion 90 of the stud in correspondence of passage 98 of tubular member 87. Said passage 98 extends all the way from threaded end 89 of tubular member 87 to the outer end 95 of 99 of enlarged portion 86 of said tubular member.

The arm holding chuck comprises a bushing member 100 which is rotatably mounted upon enlarged end 86 of tubular member 87, and which is formed with a tapering outer end 101 having a relatively thin edge 102, said tapering end being machined exactly to size at 103 to closely fit the attaching end of arm 34.

The outer surface of bushing 100 is threaded at both ends so as to be adapted to receive a threaded chuck collar 104 at its outer end and a threaded hollow nut 105 at its inner end. A washer 106 is inserted between the inner end surface of bushing 100 and the inner surface 107 of nut 105 and a packing ring 108 is inserted between said washer and said inner surface 107. This arrangement insures the tightness of the connection between the bushing and the nut and between the bushing and its support 86.

Chuck collar 104 is screwed onto the outer end of bushing 100 and has the outer end of its opening tapering as shown at 109, its tapering angle being slightly greater than the tapering angle of outer end 101 of the bushing. By virtue of this arrangement, if the chuck collar is turned so that its inner tapering surface will tightly bear against the edge 102 of the outer end of the bushing, said edge will be forced inwardly and will tightly clamp the end of the arm 84 inserted within opening 103.

In this manner, the angular position of arm 84 can be adjusted with respect to the axis

of tubular member 87 and when so adjusted said arm together with parts 100, 104, and 105 forming the chuck can rotate over its support 86 while tightness of the rotatable connection thus established is insured by packing ring 108. The outer end of arm 84 is bent in an elongated S shape as shown at 110 and its angular position with respect to the axis of tubular member 87 is adjusted so that when said arm occupies its inoperative position shown in full lines in Figs. 1, 2, 3, 4, said S shaped outer end lies in a horizontal plane just above rim 22 at the rear of the bowl within clearance 28 between the upper surface of said rim and the lower surface of seat 24. Tubular extension 87 carries two rollers 111 and 112, roller 111 passing through horizontal slot 113 provided through the vertical wall 114 of an angle shaped arm supporting member 115. Said member 115 also has a horizontally extending flange 116 which has a slot 117 within which is inserted the upward extension 118 of a cam acting dog 119 integral with bushing 100. When arm 84 is in its inoperative position shown in Figs. 1 to 4, the flat upper surface 120 of dog 119 rests against the under surface of flange 116, as Fig. 8 clearly shows, so that in this position arm 84 is prevented from turning.

If said arm however, is moved angularly about its pivotal support 83 towards the center of the bowl, the tip of extension 118 of dog 119 will strike against the edge 121 of slot 117 and will cause the arm and the chuck from which it extends to turn about the axis of tubular member 87.

Roller 112 is engaged by a cam acting slot 122 provided in a vertically movable plunger 123, said slot having an upwardly inclined portion 124 and a vertical end portion 125. Plunger 123 is guided by and slidable between two uprights 126, 127 and is normally held in its upward position shown by springs such as 128, 129. At its upper end, said plunger is equipped with a push knob 130. When downward pressure is exerted against said knob the inclined portion 124 of cam slot 122 will cause the flushing arm to move towards the center of the bowl until its proper position shown in dotted lines at 110' in Figs. 1 and 2 is reached. At this point the flushing arm becomes engaged by the vertical portion 125 of slot 122 and will be retained thereby in the same position while the plunger continues to descend. At the beginning of the inward movement of the flushing arm to operative position, its S shaped end portion will retain its horizontal alignment until having cleared the rim of the bowl, and extension 118 of dog 119 having come to rest against the edge 121 of slot 117 the arm will begin to rotate together with its chuck about the axis of tubular member 87 as explained.

65 The lower end of vertically movable plung-

er 123, which is preferably flat in shape as shown, is inserted within a slot 131 provided at the upper end of stem 50, and thus serves to maintain the proper alignment of valve controlling plunger 51 and housing 53. 70 During the first period of the movement of descent of plunger 123, while the inward movement of the flushing arm takes place, the lower edge 132 of plunger 123 travels towards the lower end 133 of slot 131.

75 When the vertical portion 125 of slot 122 begins to engage roller 112 of tubular member 87, lower edge 132 of plunger 123 meets lower edge 133 of slot 131, so that a continuation of the downward movement of plunger 123 will result in the valve controlling plunger 51 being forced downwardly against the action of spring 64. When this takes place, cam acting members 62, 63 will force valves 69, 70 outwardly so that water will be admitted to the 80 annular chamber forced by recess 78 and by the inner surface of chamber 49 and from there to passage 79 and to the flushing arm. To this end, the valve stems 67, 68 are formed with longitudinal grooves such as 134, 135, in 85 Figs. 18, 19 which will establish communication between chambers 72, 73 and said annular chamber.

90 Said longitudinal grooves 134, 135 preferably have a curved outline at their inner end as shown at 136, in Fig. 10, so that the water is admitted to or cut off gradually from the passages when the valves are opened or closed. This insures a condition whereby the 95 pressure of the water will not interfere with the operation of the valves either way, preventing a sudden inflow, and especially obviating the possibility of the valve being held open by the inrushing water after once having been forced open, an occurrence which 100 might take place if the flow of water were only controlled by the conical seat of the valves.

105 It will be observed that while cam acting member 62 is shaped to first force valve 69 outwardly and then to permit said valve to once more gradually close, once the peak 136' has been passed, cam acting member 63 will first force valve 70 outwardly, then it will allow 110 said valve to remain stationary, and then it will once more force said valve outwardly as the valve controlling plunger reaches the end of its downward stroke. By virtue of this arrangement the total flow of water controlled by the two valves will be maintained about 115 constant, since while the flow through passage 65 begins to decrease the flow through passage 66 begins to increase.

120 Valve 69 controls the cold water supply while valve 70 controls the hot water supply and by virtue of the arrangement described, it is possible, when the movement of the valve controlling plunger starts, to deliver to the flushing arm water which is entirely cold. Then when the valve controlling plunger has 125 130

reached about midway of its stroke, the water delivered would be a mixture of cold and hot water, and when the plunger has reached the end of its downward stroke, there will be no cold water delivered but only hot water. In this manner, it is possible for the user to regulate the exact temperature at which the water is delivered at the point of use. A parallel result may be obtained by means of the arrangement shown in Fig. 20 in which 5 67' is the stem of the valve controlling the cold water supply and 68' is the stem of the valve controlling the hot water supply. In this arrangement the valve controlling plunger 51' is provided with two arms 137, 138 pivotally mounted at 139, 140 respectively, said two pivots being vertically spaced from each other and pivot 140 being at a higher level than pivot 139. Arms 137, 138 have 10 curved ends shaped to engage the rounded ends of valve stems 67', 68' and therefore will form therewith a sort of toggle joint which results in valve stems 67', 68' being forced outwardly when the valve controlling plunger 51' is forced downwardly.

However, arm 137 will reach its dead point before arm 138 so that arm 138 will continue to force valve stem 68' outwardly when arm 137 permits valve stem 67' to once more move 15 inwardly after the dead point has been passed. An equivalent arrangement is shown in Fig. 21 where instead of using pivotally mounted arms we make use of two rollers 137', 138', rotatably mounted on vertical space shafts 139', 140'. In this arrangement, the action of arms 137, 138 is duplicated the 20 rollers acting as rolling cams while in the previous case arms 137, 138, act as elements of a toggle connection.

From the foregoing, it will be seen that we 25 provide a simple, practical and reliable device in which a single movement of an operating member causes the flushing arm to perform both a translatory and a rotary movement, and also causes water from suitable source of supply to reach the nozzle of 30 said arm at the proper time.

Our invention may be carried into practice 35 in ways different from that shown without departing from the inventive idea; the drawings will therefore be understood as being intended for illustrative purpose only, and not in a limiting sense. Accordingly, we 40 reserve the right to carry our invention into practice in all those ways and manners which may enter, fairly, into the scope of the appended claims.

We claim:

1. In apparatus of the class described, 45 adapted for use in connection with a closet bowl, the combination, with a support, of a fluid delivery arm provided with a nozzle at its outer end, mounted on said support, said arm having a bent outline and lying entirely in a substantially horizontal plane and

directly above the rim of the bowl when in its inoperative position, and lying in an upwardly directed plane with its nozzle within said bowl, when brought to its operative position, means for causing a substantially horizontal inward movement of said arm, and stationary means cooperating with said moving arm for causing rotatory movement of the outer portion thereof in order to bring it in said upwardly directed plane, after said outer portion has cleared the rim of said bowl. 70

2. In apparatus of the class described, adapted for use in connection with a closet bowl, the combination, with a support, of a fluid delivery arm provided with a nozzle at its outer end, mounted on said support, said arm having a bent outline and lying in a substantially horizontal plane above the rim of the bowl when in its inoperative position, and lying in an upwardly directed plane with its nozzle within said bowl, when brought to its operative position, cam acting means for causing a substantially horizontal inward movement of said arm, and cam acting means for causing rotatory movement of the outer portion thereof in order to bring it in said upwardly directed plane, after said outer portion has cleared the rim of said bowl. 80

3. In apparatus of the class described, adapted for use in connection with a closet bowl, the combination, with a support, of a tubular member mounted thereon so as to be angularly movable about a substantially vertical axis, a fluid delivery arm outwardly extending from and rotatable about the axis of 85 said member, means for causing angular movement of said member, and means cooperating with said arm for causing rotatory movement thereof when said member is displaced from one of its extreme angular positions to the other. 90

4. In apparatus of the class described, adapted for use in connection with a closet bowl, the combination, with a support, of a fluid delivery arm mounted on said support, said arm being movable from an inoperative position in which it rests entirely and directly above the rim of the bowl, to an operative position where the outer end of said arm remains within said bowl, normally inoperative means for supplying fluid to said arm, and means, causing in succession, by a single movement, inward movement of said arm to clear said rim, subsequently bringing said arm to its operative position, and thereafter actuating said fluid supply means to admit fluid to said arm. 100

5. In apparatus of the class described, adapted for use in connection with a closet bowl, the combination, with a support, of a tubular member mounted thereon so as to be angularly movable about a substantially vertical axis, a fluid delivery arm outwardly extending from and rotatable about the axis of 105 said member, means for causing angular 110 movement of said member, and means cooperating with said arm for causing rotatory movement thereof when said member is displaced from one of its extreme angular positions to the other. 115

120

125

130

- movement of said member, means cooperating with said arm for causing rotary movement thereof when said member is displaced from one of its extreme angular positions to the other, normally inoperative means for supplying fluid to said tubular member, and means controlled by said first mentioned means, for actuating said fluid supply means to admit fluid to said tubular member.
6. In apparatus of the class described, adapted for use in connection with a closet bowl, the combination, with a support, of a tubular member mounted thereon so as to be angularly movable about a substantially vertical axis, a fluid delivery arm outwardly extending from and rotatable about the axis of said member, a cam-acting plunger member for causing angular movement of said tubular member, a cam associated with said arm, and a stationary member, cooperating with said cam for causing rotatory movement of said arm, when said tubular member is displaced from one of its extreme angular positions, to the other.
7. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a cam-acting plunger member for causing angular movement of said tubular member, a cam associated with said arm, and a stationary member, cooperating with said cam for causing rotatory movement of said arm, when said tubular member is displaced from one of its extreme angular positions to the other.
8. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a stationary member providing a substantially horizontal rest for said tubular member, a cam-acting plunger member movable in proximity of said stationary member for causing angular movement of said tubular member, a cam associated with said arm, cooperating with said stationary member for causing rotatory movement of said arm, when said tubular member is displaced from one of its extreme angular positions to the other, and rollers on said tubular member for causing rolling instead of sliding friction being developed when said tubular member is displaced from one of its positions to the other.
9. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said
- member, and a cam associated with said arm, cooperating with said stationary member for causing rotary movement of said arm, when said tubular member is displaced from one of its extreme angular positions to the other.
10. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a cam-acting plunger member for causing angular movement of said tubular member, a cam associated with said arm, and a stationary member, cooperating with said cam for causing rotatory movement of said arm, when said tubular member is displaced from one of its extreme angular positions to the other, said rotatory movement taking place only after the outer portion of said arm has cleared the rim of said bowl.
11. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a stationary member providing a substantially horizontal rest for said tubular member, a cam-acting plunger member movable in proximity of said stationary member for causing angular movement of said tubular member, a cam associated with said arm, cooperating with said stationary member for causing rotatory movement of said arm, when said tubular member is displaced from one of its extreme angular positions to the other, and rollers on said tubular member for causing rolling instead of sliding friction being developed when said tubular member is displaced from one of its positions to the other.
12. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said

tubular member, said arm having a bent outline and lying in a substantially horizontal plane above the rim of the bowl when in its inoperative position, and lying in an upwardly directed plane with its nozzle within said bowl, when brought to its operative position, a stationary member providing a substantially horizontal rest for said tubular member, a cam-acting plunger member movable in proximity of said stationary member for causing angular movement of said tubular member, a cam associated with said arm, cooperating with said stationary member for causing rotatory movement of said arm, when 5 said tubular member is displaced from one of its extreme angular positions to the other, and spring means tending to maintain said plunger member in its inoperative position.

12. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a stationary member providing a substantially horizontal rest for said tubular member, 20 a cam-acting plunger member movable in proximity of said stationary member for causing angular movement of said tubular member, a cam associated with said arm, cooperating with said stationary member for causing rotatory movement of said arm, when 25 said tubular member is displaced from one of its extreme angular positions to the other, rollers on said tubular member for causing rolling instead of sliding friction being developed when said tubular member is displaced from one of its positions to the other, and spring means tending to maintain said plunger member in its inoperative position.

45 13. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a stationary member providing a 50 substantially horizontal rest for said tubular

member, a cam-acting plunger member movable in proximity of said stationary member for causing angular movement of said tubular member, a cam associated with said arm, cooperating with said stationary member for causing rotatory movement of said arm, when 55 said tubular member is displaced from one of its extreme angular positions to the other, normally inoperative means for supplying fluid to said tubular member, and means controlled by said plunger member for actuating said fluid supply means to admit fluid to said tubular member.

14. In apparatus of the class described, adapted for use in connection with a closet bowl, the combination, with a support, of a tubular member mounted thereon so as to be angularly movable about a substantially vertical axis, a fluid delivery arm provided with a nozzle at its outer end, outwardly extending from and rotatable about the axis of said tubular member, said arm having a bent outline and lying in a substantially horizontal plane above the rim of the bowl when in its inoperative position, and lying in an upwardly directed plane with its nozzle within said bowl, when brought to its operative position, a stationary member providing a substantially horizontal rest for said tubular member, a cam-acting plunger member movable in 80 proximity of said stationary member for causing angular movement of said tubular member, a cam associated with said arm, cooperating with said stationary member for causing rotatory movement of said arm, when 85 said tubular member is displaced from one of its extreme angular positions to the other, normally inoperative means for supplying fluid to said tubular member, and means controlled by said plunger member for actuating said fluid supply means to admit fluid to said tubular member, after the completion of the 90 movement of said arm to its operative position.
